GEORGE S. WITHAM, JR., OF HUDSON FALLS, NEW YORK.

MOISTURE MEASURING AND RECORDING APPARATUS.

Application filed February 14, 1924. Serial No. 692,889.

My invention relates to moisture recording apparatus.

The principles of the invention are applicable to various industries, such as the 5 paper industry, the textile industry, the manufacture of cement and other industries in which there is a flow or passage of material past a given point.

The invention will be described as employed in the manufacture of paper, but I 10 wish it understood that I do not want to be limited to its use in that specific industry.

In the manufacture of paper the web after being formed is then conducted over festoon 15 or other driers, after which it is cut and reeled up for use. The driers are preferably steam heated, and the quantity of steam admitted, so as to leave the requisite quantity 20 of moisture in the paper, is usually manually controlled by one of the machine attendants, and the quantity of steam admitted is usually dependent upon the moisture content of the paper, as determined by the "feel". It will 25 be obvious that the determination of the moisture content by the feel of the paper is dependent upon the skill and judgment of the attendant, and, even with the same attendant, various changes and conditions affect his judgment or estimate of the 30 moisture content. Heretofore devices have been proposed for determining the moisture content, which are not altogether dependent upon the judgment of an attendant. Such devices, while more or less satisfactory, are 35 usually of complicated construction and design, and are therefore not in all cases practicable for the uses to which they are put.

In my co-pending application, Serial No. 531,863 filed January 26, 1922, I have described a form of moisture recording apparatus, a part of which is designed to be either manually or automatically moved 40 across the web of paper or other material being tested, so that a determination of the moisture content of the web at any particular 45 point may be made. That apparatus, while satisfactory in most cases, involves moving parts which may get out of order and thus affect the accuracy of the determination.

In my co-pending application, Serial No. 537,328 filed February 17, 1922, I have disclosed a control apparatus designed to automatically control the admission of steam to 50 the driers, dependent upon the moisture content of the paper passing over the driers.

It is the principal object of my present invention, to provide a relatively simple form of device for indicating the moisture content of a traveling web, and one in which 60 there are few or no moving parts to get out of order.

It is a further object to provide a form of moisture indicator in which the moisture content of any selected part or the whole of 65 the traveling web may be determined by a simple manipulation of a valve or valves.

It is another object to provide improved forms of sample box for collecting a gas, for determination of the moisture content of 70 the traveling web.

In the drawings, which show for illustrative purposes only, preferred forms of the invention—

Fig. 1 is a partially diagrammatic plan 75 view of one form of my improved apparatus applied to a traveling web;

Fig. 2 is a side view of the apparatus disclosed in Fig. 1;

Fig. 3 is a longitudinal sectional view of 80 an improved form of sample box;

Fig. 4 is a plan view of the same;

Fig. 5 is an enlarged sectional view taken substantially in the plane of the line 5—5 of Fig. 3;

Fig. 6 is a plan view of a modified form 85 of sample box;

Fig. 7 is a sectional view taken substantially in the plane of the line 8—8 of Fig. 6;

Fig. 8 is a plan view of a further modified 90 form of sample box;

Fig. 9 is a sectional view taken substantially in the plane of the line 10—10 of Fig. 8;

Fig. 10 is a plan view of still another form 95 of sample box;

Fig. 11 is a sectional view taken substantially in the plane of the line 12—12 of Fig. 10;

Fig. 12 is a plan view of a further modification 100 of a sample box;

Fig. 13 is a sectional view taken substantially in the plane of the line 14—14 of Fig. 12;

Fig. 14 shows another form of sample 105 box; and

Fig. 15 is a section taken substantially in the plane of the line 16—16 of Fig. 14.

In the drawings, 1—2 represent two driers, constituting part of a series of driers for a 110 traveling web of paper 3. The paper, after leaving the last or sweat drier 1, passes over

a spring roll 4 and then over a series of calender rolls, not shown. While it is possible to ascertain the moisture content of the traveling web at any desired point, I believe it is best to make that determination just in advance of the last sweat drier, for by that drier some previous errors in the manufacture may be corrected. I therefore prefer to position my improved form of sample box 5 against the traveling web, just before the latter reaches the last sweat drier 1. The sample box may be secured to the frame of the machine in any suitable manner, and is preferably fixedly mounted and extends 10 15 preferably completely across the traveling web.

6 indicates a blower for drawing gas, such as air, through the gas modifier which, in the form shown, is a radiator 7 for conditioning or cooling the air. The air or gas, after passing through the blower 6, passes through the conduit 8 to the sample box 5. The gas passing through the sample box absorbs or takes up moisture from the traveling web and is also heated to an extent dependent upon the temperature of the web. The heated and moist or humidified gas leaves the sample box 5 and, by means of the conduit 9, passes to some form of hygrometer 30 or hygroscope 10 which, in the form shown, is a wet and dry bulb psychrometer. 11 indicates the dry bulb, while 12 indicates the wet bulb, having gauze or other suitable means for maintaining the same in a moist condition. After passing through and acting on the psychrometer 10 the air or gas is released to the atmosphere.

13 designates any suitable form of recording mechanism for recording the differences 40 in temperature of the wet and dry bulbs. The dial or chart placed on the recorder 13 may, of course, be calibrated to read differences in temperatures, or may be calibrated to read the moisture content directly as will 45 be understood.

Such is the general construction and application of my invention.

The preferred form of sample box disclosed in Figs. 3, 4 and 5 preferably comprises a long shallow box extending completely across the traveling web. The box itself is provided with a plurality of channels 15, 16 and 17, extending from end to end thereof. One wall 18 of the box serves 50 55 to separate the channels from the trough formed by this wall 18 and the rails 19-19 secured thereto and preferably rounded, as shown. The shallow passage or trough formed by the wall 18 and the rails 19 is 60 divided by partition members 20-21, so as to divide the shallow trough into three compartments and end rails or stops 22-23 serve to define the ends of the two end compartments. At one end the sample box has 65 a connection 24 for receiving the conduit 8,

for conveying the gas or air from the blower to the sample box. In the preferred form this section 24 carrying the intake connection is preferably removably secured to the box as by means of screws (not shown). 70 The connection 24 is in communication with all of the channels and permits the air or gas to enter. The opposite end of the sample box is also provided with a connection 25, for receiving the discharge conduit 9, which 75 conducts the air to the hygrometer after passage across the traveling web. The connection 25 is preferably removably secured to the sample box by means of a screw or the like (Fig. 3), so as to permit cleaning and 80 inspection. All of the channels are adapted to communicate with the connection 25 and the discharge conduit 9, but each channel is controlled by valves 26, 27 28 so that one or all of the channels may be shut off by 85 means of their respective valves. When one of the valves, for example valve 27, is opened, that is, moved toward the right as viewed in Fig. 4, the channel 16 is opened. If the valves 26, 27 are closed and the valve 28 opened, the channel 17 is free for the 90 passage of air. The channel 15 is likewise controlled by the valve 26.

While the channels in the sample box 95 preferably extend entirely along the sample box, each channel is so interrupted as to cause the air or gas from the conduit 8 to pass out of the channel and upwardly into a shallow trough formed by the wall 18, rails 19-19 and partitions 20-21, so as to cause 100 the air from that channel to come in close contact with the traveling web and thus be affected by the temperature and moisture content of the web. In the form shown each channel has a block 29 therein (clearly shown in Fig. 5) and the wall 18 is provided in each of the three compartments with inlet and outlet apertures. The left-hand box thus has the inlet aperture 30 and the outlet aperture 31. The middle compartment has 105 inlet and outlet apertures 32, 33 respectively, while the right-hand compartment has corresponding apertures 34, 35 respectively. 110

It will thus be seen that with the valves 115 positioned as shown in Fig. 4, that is, with the middle channel 16 open, air or gas may enter all the channels, but since channels 15 and 17 are closed by the valves 26, 28, only the channel 16 will be free for the passage of air to the outlet 9. Air will then 120 pass along the channel and, upon reaching the aperture 32 in the wall 18, will come out into the shallow central trough and will there absorb moisture and be heated by the traveling web of paper or other material. The gas then passes out through the outlet aperture 33 and again into the channel, and thence out through the outlet conduit 9 to the hygrometer 10, where the moist air 125 affects the readings of the wet and dry bulbs 130

and gives an indication of moisture content. By manipulating the valves 26, 27, 28 any one of the channels may be opened to the passage of gas, so that either of the three sections of the traveling web may be tested. If all of the valves are opened, the gas is free to pass through all of the channels and shallow troughs in contact with the web, and the moisture content of the entire width 10 of web will then be reflected in the hygrometer. It will be noted that the pressure in the sample box is above that of the atmosphere and, while a negligible quantity of air may escape between the box and web, no 15 air is drawn into the box at this point to contaminate the testing air current as might be the case if the pressure in the sample box was below that of the atmosphere.

If necessary a tie rod 35' adjustable by 20 means of a turn buckle as shown in Fig. 3, may be employed for preventing the sample box from sagging.

In the form shown in Figs. 6 and 7 there are also provided three channels 36, 37 and 25 38. Each of these channels is partitioned off so that the channel 36 includes approximately one-third of the width of the sample box. The channel 37 includes approximately two-thirds the width of the box, while the channel 38 includes practically the entire width 30 of the box. Air or gas entering the conduit 8 may enter any one of the channels, as will be clear from Fig. 6, depending upon which of the valves 39, 40 or 41 may be open to 35 permit such passage of air.

In the form shown in Figs. 8 and 9 air enters through the conduit or connection 8, and thence may pass into any one of the chambers 42, 43, 44, but since these chambers or troughs are controlled by means of 40 valves 45, 46, 47, no gas may flow until one of these valves is opened. If the valve 46, for example, is open, gas may pass through conduit 8 into the trough 43, where it will 45 be affected by the temperature and humidity of the web traveling across the face of the sample box, and thence past the valve 46 to conduit 9 and to the hygrometer. It will be noted that in this form of construction 50 each valve stem is practically parallel with the traveling web and is in close proximity thereto.

In the form shown in Figs. 10 and 11 air or gas may enter through conduit 8. In this 55 form there are also three compartments 48, 49, 50, which, as in the preceding forms, are covered by the traveling web. Each of these compartments is controlled by a valve 51, 52, 53 respectively. If, therefore, one of 60 the valves, for example, valve 52, is open, as shown in Fig. 11, air or gas flowing in conduit 8 will pass outwardly through the slot or aperture 54, thence in contact with the traveling web, through the shallow trough and past the valve 52 and into the

conduit 9, from which it passes to the hygrometer. The other compartments are similarly controlled. In this form of apparatus it will be noted that a very shallow trough is provided, insuring good contact 70 with the traveling web, and the valves are at right angles to the web and removed therefrom for ease in manipulation.

Figs. 12 and 13 disclose still another modification in which three compartments 75 55, 56 and 57 are formed. The compartments are located between the conduits or channels 8 and 9, and double valves 58, 59, 60 control the passage of air or gas from and to said channels, respectively. If one 80 of the valves, for example, the valve 59, is open, gas passing through the conduit 8 will pass the end valve, thence through the central compartment in contact with the traveling web, and then to the conduit 9, from 85 which it goes to the hygrometer.

Figs. 14 and 15 indicate a form of sample box formed of tubes or pipes. In that form air or gas enters through the conduit 8 into a central cylindrical channel 61. Within 90 said channel 61 is a valve tube 62, extending beyond one end of the sample box, and there provided with means, such as a hand wheel 63, for rotating the same. Surrounding and spaced from the central channel member 61 is a second pipe or conduit 64, which is secured to the channel 61 by means of tubes 65, 65, which also serve to afford communication between the channel 61 and the trough 66 formed by the pipe 64 and the rails 67, 67, 100 secured thereto across which the web passes. The inner valve tube 62 is provided with valve apertures 68, 69, 70, in line with the short pipes or tubes 65, 65, so that upon rotation of the valve tube one of the apertures 68, 69, 70 communicates with one of the tubes and permits the air or gas to enter one of 105 the three compartments or shallow troughs formed by the rails 67-67 and divided, as by means of the partitions 71, 72, and end members 73-74 are, of course, provided, so that the end compartments are closed. The gas, after passing through one of the valve pipe apertures and into the shallow trough, 110 passes along the web, absorbing moisture and becoming heated thereby, after which the gas or air enters one of the passages 75, 76, 77 in the outer tube 64, and thence through the annular space between the tubes 61, 64 to 115 the conduit 9, which conducts the same to the hygrometer.

It will thus be seen that with all forms of sample box which have been disclosed, it is possible to test a part or the whole of the traveling web.

While I have described preferred forms of the invention, I do not wish to be strictly limited thereto, for changes may be made within the scope of the invention as defined in the appended claims.

I claim:

1. In a device of the character described, a sample box including a plurality of compartments in communication with the material to be tested, means for passing a current of gas through one of said compartments and in contact with a portion of the material to be tested, means for preventing a flow of gas to the remainder of said compartments, 10 and a hygrometer to be affected by the gas passed through said box, said hygrometer being located in the path of the gas after contact of the latter with said material.

2. In a device of the character described, 15 a sample box including a plurality of compartments in communication with the material to be tested, means for passing a current of gas through any one of said compartments and in contact with the material to be tested, 20 and a hygrometer to be affected by the gas passed through said compartment, said hygrometer being located in the path of the gas after contact of the latter with said material.

3. In a device of the character described, 25 a sample box at least a portion of which is in communication with the material to be tested, means for passing a current of gas through said sample box, valve means for blocking a portion of said box and causing 30 the gas to flow through a portion thereof and in contact with a portion of the material to be tested, and a hygrometer to be affected by the gas passed through such selected portion of said box, said hygrometer being 35 located in the path of the gas after contact of the latter with said material.

4. In a device of the character described, a sample box to be mounted adjacent the material to be tested, said box having a 40 plurality of valve controlled passages therein in communication with the material to be tested, means for passing gas through said passages and in contact with the material to be tested, and a hygrometer to be affected 45 by the gas passed through said passages, said hygrometer being located in the path of the gas after contact of the latter with said material.

5. In a device of the character described, 50 a sample box to be mounted adjacent the face of a traveling web and in communication therewith, said box being divided into a plurality of sections, and means for admitting a current of gas to any one of said sections and in contact with the traveling web and a hygrometer to be affected by the gas after passing over the web, said hygrometer being located in the path of the gas issuing from said box.

6. A material testing device of the character described, comprising a plurality of conductors each having an open side arranged adjacent to and substantially closed 65 by said material for subjecting currents of gas passing through said conductors to inti-

mate contact with different portions, respectively, of the surface of said material, gas circulating means for producing said currents, and closure means for said conductors, respectively, for directing said gas currents 70 therethrough, selectively.

7. A material testing device of the character described, comprising a plurality of conductors each having an open side arranged adjacent to and substantially closed by said material for subjecting currents of gas passing through said conductors to intimate contact with different portions, respectively, of the surface of said material, means for producing a current of gas through any of said 80 conductors, selectively, and humidity responsive means subjected to said gas currents after contact thereof with said material.

8. In a device of the character described, a box having an open side for cooperation with the surface of a material to be tested to define in conjunction with the latter an enclosed zone, means for supplying gas to said zone and discharging the same therefrom, means for selectively directing such gas to any one of a plurality of sections of said zone, and humidity responsive means located in the path of the gas after contact of the latter with said material.

9. In a device of the character described, a box having an open side adapted to be arranged adjacent the surface of the material to be tested to define in conjunction therewith an enclosed zone, partitions dividing said zone into a plurality of separate sections 100 each communicating with said material, means for circulating gas through any of said sections, selectively, at a pressure above that of the atmosphere, and humidity responsive means located in the path of said 105 gas after contact thereof with said material.

10. In a device for indicating the moisture content of a traveling web, a fixedly mounted sample box to be engaged by the traveling web and extending across the latter, said box having a plurality of compartments over which the web may pass, means for causing a current of gas to pass through any one of said compartments and in contact with said web, and a hygrometer to be affected by the 110 current of gas after passing through said compartment and in contact with the web, said hygrometer being located in the path of the gas issuing from said sample box.

11. In a device for indicating the moisture content of traveling material, a plurality of chambers each to communicate with a part of the traveling material, means for passing a current of gas to contact with the material and through either of said chambers, and means to be acted upon by the gas after passing in contact with the material for indicating the moisture content thereof.

12. Apparatus for ascertaining the moisture content of an object, comprising a sam-

ple box having an open face and an interior chamber subdivided into separate compartments all opening through said open face but over different sections of the surface of the object, said box being disposed with its open face in close proximity to and substantially closed by the surface of said object whose moisture content is to be ascertained, means by which a suitable gas may be passed selectively through said compartments so as to come into contact with selected sections of the surface of the object and have its humidity modified by the section of said surface of the object which closes the particular compartment through which the gas may be passing, and means for ascertaining the humidity of the gas after contact thereof with said surface in one of the said compartments, and thereby obtaining an indication of the moisture content of the section of the object surface which closes said one of the compartments.

ture content of an object, comprising a sample box having an open face and an interior chamber subdivided into separate compartments all opening through said open face but over different sections of the surface of the object, said box being disposed with its open face in close proximity to and substantially closed by the surface of said object whose moisture content is to be ascertained, means by which a suitable gas may be passed selectively through said compartments so as to come into contact with selected sections of the surface of the object and have its humidity modified by the section of said surface of the object which closes the particular compartment through which the gas may be passing, a common conduit through which passes the gas leaving all active compartments, and means associated with said conduit for indicating the humidity of the gas in said conduit.

13. Apparatus for ascertaining the mois-
